ATTYS.

UNITED STATES PATENT OFFICE.

JOHN A. CAMPBELL, OF QUINCY, MASSACHUSETTS.

DRESSING-MACHINE FOR FLOORS, &c.

1,279,082.

Specification of Letters Patent. Patented Sept. 17, 1918.

Application filed May 7, 1918. Serial No. 233,036.

To all whom it may concern:

Be it known that I, JOHN A. CAMPBELL, a citizen of the United States, residing at Quincy, in the county of Norfolk and State of Massachusetts, have invented new and useful Improvements in Dressing-Machines for Floors, &c., of which the following is a specification.

This invention relates chiefly to a machine for imparting smooth surfaces to floors and other structures, either of wood, or any other material, capable of being reduced or worn away by a rotating abrasive tool, pressed while rotating against the surface on which it acts, the machine being movable by the operator, to extend the grinding and polishing action in various directions.

The invention consists in the improvements hereinafter described and claimed.

20 Of the accompanying drawings forming a part of this specification,—

Figure 1 is a plan view of a machine embodying the invention.

Fig. 2 is a section on the plane of line 2—2 of Fig. 1, the motor being shown in elevation.

Fig. 3 is an end view, certain parts being omitted.

Fig. 4 is a plan view of a portion of the body of the machine.

Fig. 5 is a section on line 5—5 of Fig. 4.

Fig. 6 is a section on line 6—6 of Fig. 4, the motor and certain other parts being removed.

35 The same reference characters indicate the same parts in all of the figures.

12 represents a body adapted to be supported by and to tilt lengthwise on the running gear hereinafter described, said body being preferably oblong, as shown by Fig. 1, and provided at one end with a vertical bearing 13, and above this with a horizontal bearing 14. I use the terms vertical and horizontal relatively, it being understood

45 that when the body is tilted or inclined from a horizontal position the bearing 13 is not absolutely vertical, and the bearing 14 is not absolutely horizontal. Said bearings are a part of an upstanding bracket, the base of

50 which is secured to the body.

The removable top portion of the bearing 14 is secured to the lower portion thereof by bolts 15. The vertical bearing 13 projects forward from the body portion of the bracket, and the bearing 14 is located at the upper end of said body portion. Each bear-

ing is therefore exposed and adapted to be conveniently lubricated.

In the bearing 13 is journaled a vertical tool-operating shaft 16, the lower end of which is provided with a bevel gear 17, and its upper end with a bevel gear 18. A bracket 20 attached to the frame of the machine and having arms or ears 21, supports a shaft 22 and the shaft 23 of a cylindrical 65 abrading tool 24 adapted to act on a floor, or other surface. The shaft 22 is provided with a bevel gear 22^a meshing with the gear 17, and with spur gears 22^b meshing with spur gears 23^b on the tool shaft 23. 70

The end of the body opposite the end having the bearing 13 is provided with rigidly attached push bars 25 connected by a cross-bar 26, these forming a controlling handle.

The body 12 is provided with running 75 gear permitting its convenient transportation, and also permitting it to tilt and exert downward pressure on the tool, and compensate for wear thereof. Said running gear includes a transverse axle 27 located under the body between the ends thereof, and provided with a pair of traction wheels 28, which may have rubber tires, if desired. The axle is rigidly connected with the body, and the arms of the axle on which the wheels 80 are journaled, by turning slightly in the wheel hubs, permit a longitudinal tilting of the body.

The connections between the axle and the body are of such nature that the body is adjustable toward and from the axle to vary its height. Said connections comprise vertical twin standards 29, journaled at their lower ends in the axle, and adapted to be rotated to raise and lower the body. The 95 standards are screw-threaded above the axle, and are adjustably connected with the body 12, to permit the body to be raised and lowered.

The standards 29 pass through slots 30 100 in the body 12, and are engaged with nuts 31 bearing on the upper surface of the body at opposite edges of the slots. The standards 29 pass through openings in a cross-bar 32 which is in sliding contact with the under side of the body 12. Clamping wing nuts 33 engaged with the threads of the standards 29 bear on the under side of the bar 32. When said nuts are tightened, the bar 32 and nuts 31 are clamped against the 110 lower and upper sides of the body 12, respectively, so that the standards 29 are pre-

vented from moving lengthwise of the body, and are also prevented from rotating in the nuts 31. When the clamping nuts 33 are loosened, the standards 29 are free to be rotated, and thus raise or lower the nuts 31, rotation of said nuts being prevented by portions 31^a thereof which project into the slots 30. When the standards are rotated to raise the nuts 31, the clamping nuts 33 are correspondingly turned to maintain the cross-bar 32 in contact with the body 12, and said body in contact with the nuts 31. When the standards are rotated to lower the nuts 31, the clamping nuts 33 are correspondingly lowered. Longitudinal adjustment of the standards 29 relatively to the body 12 is effected by moving the bar 32 by means of an adjusting screw 36 journaled in a bearing 37 attached to the body 12 and having a screw-threaded engagement with a tapped orifice in an ear 37 on the bar 32, the clamping nuts being loosened. The adjusting-screw 36 is provided with a hand wheel 38 whereby it may be rotated to simultaneously adjust the standards 29 lengthwise of the body 12.

The vertical adjustability of the body 12 enables the body to be raised to a minimum height when the operating tool is practically unworn, and to be lowered to compensate for wear of the acting face of the tool.

The longitudinal adjustability of the body 12 relatively to the running gear permits regulation of the degree of downward pressure exerted by the body and its adjuncts on the tool, this pressure increasing with an increase of the distance between the tool-operating shaft 16 and the running gear.

A motor 40 of any suitable type is mounted on the body at a suitable point between the ends thereof. I have here shown more or less conventionally an electric motor supplied with current through a flexible cable 41, the circuit connections including a switch 42 mounted on the frame of the motor, and so arranged that the current can be turned on and off conveniently by an operator grasping the controlling handle. A gasoline or other suitable motor may be used instead of an electric motor.

The shaft 43 of the motor is connected with the tool-operating shaft 16 by the means next described. 44 represents a horizontal shaft journaled in the bearing 14 and provided at one end with a spur gear 46 and at the other end with a bevel gear 47. The motor shaft 43 is provided with a spur gear, not shown, meshing with the gear 46, and the bevel gear 18 on the tool-operating

shaft 16 meshes with the gear 47. The said gears are proportioned to suitably reduce the speed between the motor shaft and the tool-operating shaft.

It will be seen that the above-described machine is of simple construction and adapted to maintain the acting portions of a rotary grinding or polishing wheel in suitable contact with a floor, regardless of the reduction in the height of the tool due to wear. It will also be seen that the downward pressure of the tool against the floor may be conveniently varied as the work may require.

I claim:

1. A machine of the character stated, comprising a body having longitudinal slots, running gear including an axle and wheels thereon, screw-threaded standards journaled in the axle and projecting upwardly therefrom through said slots, nuts engaged with said standards above the body and confined against rotation, a cross bar movable on the under side of the body and having orifices through which the standards pass, clamping nuts engaged with said standards below the body and adapted to bear on said cross bar and support the body at various heights, and an adjusting screw journaled in a bearing on the body and having a screw-thread connection with said cross bar, whereby the cross bar, standards, and running gear may be horizontally adjusted relatively to the body.

2. A machine of the character specified, comprising a body having a vertical bearing and upper and lower pairs of horizontal bearings below the vertical bearing, a vertical shaft journaled in the vertical bearing and having a bevel gear at its lower end, a horizontal shaft journaled in the upper horizontal bearings and having a bevel gear meshing with the bevel gear on the vertical shaft, and a pair of spaced apart spur gears at opposite sides of said bevel gear, a rotary cylindrical dressing tool whose shaft is parallel with the horizontal shaft and is journaled in the lower horizontal bearings and provided with spur gears meshing with the spur gears on the said horizontal shaft, a motor mounted on said body, driving connections between the motor shaft and the said vertical shaft, and running gear including an axle secured to the body parallel with said horizontal shaft and with the axis of said tool and wheels on said axle constituting bearings which permit the body to swing and raise and lower said tool.

In testimony whereof I have affixed my signature.

JOHN A. CAMPBELL.
